STEAM GENERATOR

Lewis W. Heller, East Orange, N. J., assignor to
 The Babcock & Wilcox Company, Newark, N. J.,
 a corporation of New Jersey

Application March 16, 1938, Serial No. 196,120

11 Claims. (Cl. 122—336)

This invention relates to the construction and operation of steam generators of the integral furnace type, i. e., a steam generator having its furnace chamber laterally adjoining the main bank of steam generating tubes. In steam generators of this type the furnace chamber and space containing the main tube bank are usually separated except at one end, and the fuel burning means located at the opposite end of the furnace chamber. Such an arrangement generally provides a path of flame travel of adequate length in the furnace chamber with some units using certain fuels and burners, but for higher steam generating and fuel burning capacities or limitations in the floor space available, or with other fuels or burners, a longer path of flame travel is desirable to insure the desired completeness of combustion within the furnace chamber before the gases reach the tube bank and steam superheating tubes.

The main object of my invention is the provision of a steam generator of the type described with an improved construction and arrangement of the furnace and tube bank chambers and associated fluid heating parts affording a relatively long path of flame travel before the heating gases enter the tube bank and a thermally effective heating gas flow over the convection heated surface, while maintaining a compact construction having low floor space and head room requirements.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a vertical section taken on the line 1—1 of Fig. 2 illustrating somewhat diagrammatically one embodiment of the invention;

Fig. 2 is a horizontal section taken on the line 2—2 of Fig. 1;

Figs. 3 and 4 are longitudinal vertical sections taken on the lines 3—3 and 4—4 respectively of Fig. 1; and

Fig. 5 is a vertical section taken on the line 5—5 of Fig. 2.

The steam generating unit illustrated comprises a setting substantially rectangular in horizontal and vertical cross-section including a front

wall 10, a rear wall 11, side walls 12 and 13, and roof 14. A lower drum 15 is horizontally arranged along the lower part of the side wall 13 and above the bottom of the furnace chamber. A steam and water drum 16 extends parallel to the drum 15 along the roof 14 at a location inwardly offset from the drum 15. The drums 15 and 16 extend the full length of the setting and are connected by a bank of vertically disposed substantially L-shaped water tubes 17 having their ends radially connected to the drums. The space containing the tube bank is separated from the remaining portion of the setting by fluid cooled partition means hereinafter described, the remaining portion serving as the furnace chamber of the unit.

The furnace chamber is defined by the side wall 12 and portions of the walls 10 and 11 and roof 14. The furnace chamber walls are fluid cooled, the fluid cooling provisions comprising front wall tubes 19 and rear wall tubes 20 lining the front and rear walls respectively. The tubes 19 and 20 have their upper ends bent laterally into the upper drum 16 and their lower ends connected to headers 21 and 22 respectively connected to the drum 15. The side wall 12 and roof 14 are cooled by a row of tubes 23 extending from a lower side wall header 24 to the upper drum 16. The bottom of the furnace chamber is defined for substantially its entire length by a fluid cooled floor 25 formed by a row of block covered tubes 26 extending from the header 24 to a similar header 27 below the drum 15. The floor 25 extends from the rear wall 11 and terminates short of the front wall, the remaining portion of the furnace chamber bottom being formed by an ash pit 29.

The partition-forming means separating the furnace chamber from the tube bank space comprise a row of tubes 35 at the inner side of the tube bank extending downwardly from the drum 16. The tubes 35^a in the rear portion of the tube row 35 continue downwardly and are connected to the subjacent tubes 26 by incorporating an intermediate floor header 28 in the rear portion of the tube row 26. The remaining tubes 35 are bent laterally toward the drum 15 and thence along the lower portion 13^a of the side wall 13 to the header 27. The tubes 35 and 35^a are partially studded to support refractory closing the intertube spaces and thus form a partition 37 having a vertically extending upper portion, a vertical lower rear portion 37^a and a laterally inclined front portion 37^b. The partition construction described thus defines a furnace

chamber having a laterally extending leg over a major portion of its length from the front wall rearwardly and an entrance into the tube bank space behind the partition section 37^a.

The partition construction described is especially adapted for the provision of a relatively long path of flame travel in the furnace chamber with a fluid fuel burner located in the rear wall 11 or roof 14. As shown in Figs. 1 and 3, a rectangular fuel burner port 40 is formed in the roof 14 adjacent the rear wall 11. A portion of the tubes in the tube row 23 are bent, as shown in Fig. 3, in an inclined plane in spaced relation across the burner port. A pair of pulverized fuel burner nozzles 41 of the multiple-outlet type are arranged side-by-side in the burner port with the burner outlets having their longitudinal axes intersecting the axes of the corresponding tube portions, whereby the streams of primary air and pulverized fuel issuing from the nozzles are divided by the subjacent tube portions and pass through the intertube spaces into the furnace chamber. A secondary air casing 42 encloses the burner nozzles 41 and burner port 40 and provides a stream of secondary air around the burner outlets and through the inter-tube spaces. With this construction streams of pulverized fuel and combustion air are directed downwardly and forwardly in the furnace chamber. Combustion will proceed at a relatively rapid rate, and the products of combustion flow laterally below the partition section 37^b and rearwardly behind the partition section 37^a into the bottom of the tube bank space.

The tube bank space is advantageously divided into a plurality of serially connected passes by the baffle system hereinafter described. As shown in Fig. 1, the tubes 17^a forming the outermost row of tubes have their upper portions bent laterally to the side wall 13 before entering the drum 16. Baffle blocks are arranged to form a baffle 45 following the configuration of the tubes 17^a from the lower drum 15 to the upper part of the rear wall 13, the bent upper portion of the tubes 17^a serving to support the baffle blocks. The baffle 45 extends from the front wall rearwardly to the same extent as the partition section 37^b. A vertical baffle 46 extends downwardly through the tube bank to its full extent and laterally from the partition 37 to the full width of the tube bank, and also closes the rear end of the space within the baffle 45. The space between the baffle 46 and the rear wall 11 forms a gas pass 50 through which the heating gases flow upwardly and then forwardly through the triangular space defined by the upper portions of the tubes 17^a at the outer side of the baffle 46. This triangular space is closed at a point forwardly of the baffle 46 by a second transverse baffle 47 which also extends the full width of the tube bank and terminates at its lower end across the inclined portion of the tubes 17, as indicated in Fig. 1. The baffle 47 thus divides the space forwardly of the baffle 46 into a second pass 51 through which the heating gases flow downwardly and laterally, and a third gas pass 52 through which the heating gases flow laterally and upwardly to a gas outlet 53 at the front end of the tube bank space.

The portion of the tube bank 17 in the first gas pass 50 is formed by a small number of tube rows 17^b of larger diameter than the remaining tubes in the bank. The inclined portions of the tubes in the two lower rows 17^b are spaced and arranged, as shown in Fig. 4, to provide a slag screen across the entrance to the first pass 50.

The remaining portion of the gas pass 50 is occupied by a group of vertical superheater tube coils 55 arranged in a multiple horizontal looped formation. Each superheater tube coil has its horizontally extending legs interconnected by supporting lugs 56 and the coil is suitably supported as a whole at opposite ends from the adjacent tubes 17^b and wall 13. The upper ends of the superheater tube coils 55 are connected to the steam space of the drum 16, while their lower ends are connected to the steam main. With this arrangement of the heating surface in the first pass the heating gases flow upwardly over the tubes 17^b and superheater tubes, then around the upper portion of the baffle 46 and over the baffle 45 into the second pass 51. The gases flow downwardly therein along the tubes 17 and around the lower end of the baffle 47 into the third pass 52, wherein the gases flow upwardly through the tube bank opposite to the gas flow in the pass 51.

With the arrangement of the generating tubes 17^b and superheater coils illustrated, the heating gases flowing upwardly through the first pass 50 may tend to short-circuit part of the superheating surface due to the greater gas flow area in the pass adjacent the partition 37. The distribution of the heating gases and thereby the amount of superheating effected is controlled, as shown in Fig. 5, by the arrangement of a vertical baffle 58 at the inner end of the superheater coils. The baffle divides the gas pass 50 longitudinally and terminates short of the drum 16, with the space therebetween controlled by a pivoted damper 59 adapted to be externally operated. The position of the damper will control the amount of heating gases passing upwardly between the partition 37 and baffle 58.

The described steam generator construction provides a somewhat reverberatory flame path of substantial length in the furnace chamber, which expedites combustion and insures an adequate length of flame travel at high rates of fuel introduction. The particular tube bank and baffle formation employed permits this long flame path in the furnace chamber, and also provides a thermally effective flow of heating gases over the convection heated surface.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A steam generator comprising an upper horizontally elongated drum and a laterally displaced lower drum, a bank of L-shaped steam generating tubes connecting said drums, partition means separating an L-shaped space containing said tube bank from one side of a furnace chamber extending along the outer side of and partly below the L-shaped space containing said tube bank and communicating therewith adjacent one end thereof, and means for burning fuel in said furnace chamber and causing a flow of heating gases from said furnace chamber longitudinally of the L-shaped space containing said tube bank.
2. A steam generator comprising an upper horizontally elongated drum and a laterally dis-

placed lower drum, a bank of L-shaped steam generating tubes connecting said drums, partition means separating the space containing said L-shaped tube bank from one side of a furnace chamber extending along one side of and partly below the space containing said tube bank and communicating therewith adjacent one end thereof only, and means at the communicating end of said furnace chamber for discharging a stream of fluid fuel in said furnace chamber and burning the fuel in suspension therein.

3. A steam generator comprising an upper horizontally elongated drum and a laterally displaced lower drum, a bank of L-shaped steam generating tubes connecting said drums, partition means defining one side of a furnace chamber extending along one side of and partly below the space containing said tube bank and communicating therewith adjacent one end thereof only, means at the communicating end of said furnace chamber for discharging a stream of fluid fuel in said furnace chamber and burning the fuel in suspension therein, and means defining a plurality of serially connected vertical gas passes longitudinally of said tube bank.

4. A steam generator comprising an upper horizontally elongated drum and a laterally displaced lower drum, a bank of L-shaped steam generating tubes connecting said drums, means defining a furnace chamber extending along one side of and partly below the space containing said tube bank and communicating therewith adjacent one end thereof only, said means comprising a fluid cooled partition extending downwardly from said upper drum and divided into a portion extending laterally below said tube bank and a portion extending vertically to the bottom of said furnace chamber, and means for burning fuel in suspension in said furnace chamber.

5. A steam generator comprising an upper horizontally elongated drum and a laterally displaced lower drum, a bank of L-shaped steam generating tubes connecting said drums, means defining a furnace chamber extending along one side of and partly below the space containing said tube bank and communicating therewith adjacent one end thereof only, said means comprising a row of partition-forming water tubes extending downwardly from said upper drum and divided into a group of L-shaped tubes extending laterally below said tube bank and a group of vertical tubes extending to the bottom of said furnace chamber, means closing the intertube spaces of said partition tubes, and means for burning fuel in said furnace chamber.

6. A steam generator comprising an upper horizontally elongated drum and a laterally displaced lower drum, a bank of L-shaped steam generating tubes connecting said drums, means defining a furnace chamber extending along one side of and partly below the space containing said tube bank and communicating therewith adjacent one end thereof only, said means comprising a partition extending downwardly from said upper drum and having a portion extending laterally below said tube bank, means for burning fuel in said furnace chamber, and means defining a plurality of serially connected vertical gas passes longitudinally of the space containing said tube bank.

7. A steam generator comprising an upper horizontally elongated drum and a laterally displaced lower drum, a bank of L-shaped steam generating tubes connecting said drums, means

defining a furnace chamber extending along one side of and partly below the space containing said tube bank and communicating therewith adjacent one end thereof only, said means comprising a partition extending downwardly from said upper drum and having a portion extending laterally below said tube bank and a portion extending vertically to the bottom of said furnace chamber, means for burning fuel in said furnace chamber, and means defining a plurality of serially connected vertical gas passes longitudinally of the space containing said tube bank, said last named means including a horizontally disposed V-shaped baffle at the opposite side of said tube bank, and a pair of vertically disposed baffles extending between said partition and said V-shaped baffle.

8. A steam generator comprising an upper horizontally elongated drum and a laterally displaced lower drum, a bank of L-shaped steam generating tubes having laterally extending lower portions connected to the lower drum and vertically extending upper portions connected to the upper drum, means separating the space containing said L-shaped tube bank from a furnace chamber extending along one side of and partly below the space containing said tube bank, said means including a partition extending downwardly from said upper drum at the furnace chamber side of said tube bank and having a lower portion extending laterally below said tube bank, a heating gas outlet from said furnace chamber into said tube bank space arranged below laterally extending tube portions and providing a heating gas flow upwardly across said laterally extending tube portions, and means for burning fuel in said furnace chamber.

9. A steam generator having walls forming a setting, a horizontally elongated steam and water drum, means forming a furnace chamber in said setting having a lateral extension and partly separated from a convection space in said setting located above said furnace chamber extension, said means including L-shaped steam generating tubes having vertically extending upper portions connected to said drum and closure means cooperating with said L-shaped tubes to form a partition extending downwardly from said drum at the furnace chamber side of said convection space and having a lower portion extending laterally below said convection space, a gas outlet in said partition lower lateral portion connecting said furnace chamber extension to said convection space, fluid heating tubes arranged in said convection space, and baffle means dividing said convection space into serially connected upflow and downflow heating gas passes below the level of said drum and containing said fluid heating tubes.

10. A steam generator having walls forming a setting, a horizontally elongated steam and water drum, means forming a furnace chamber in said setting having a lateral extension and partly separated from a convection space in said setting located above said furnace chamber extension, said means including L-shaped steam generating tubes having vertically extending upper portions connected to said drum and closure means cooperating with said L-shaped tubes to form a partition extending downwardly from said drum at the furnace chamber side of said convection space and having a lower portion extending laterally below said convection space, a gas outlet at one end of said partition lower lateral portion connecting said furnace chamber

extension to said convection space, baffle means dividing said convection space into an upflow heating gas pass opening to said gas outlet and a serially connected downflow heating gas pass extending below the level of said drum, fluid heating tubes located in said heating gas passes, and a group of said L-shaped tubes having their lower portions arranged to form a tube screen across said gas outlet.

11. A steam generator having walls forming a setting, a horizontally elongated steam and water drum, means forming a furnace chamber in said setting having a lateral extension and partly separated from a convection space in said setting located above said furnace chamber extension, said means including L-shaped steam generating tubes having vertically extending upper portions

connected to said drum and closure means cooperating with said L-shaped tubes to form a partition extending downwardly from said drum at the furnace chamber side of said convection space and having a lower portion extending laterally below said convection space, a gas outlet from said furnace chamber extension upwardly into said convection space, fluid heating tubes arranged in said convection space, baffles dividing said convection space into serially connected upflow and downflow heating gas passes containing said fluid heating tubes, a bank of steam heating tubes located in an upflow pass opening to said gas outlet, and a damper controlled by-pass passage arranged in parallel with said upflow pass.

LEWIS W. HELLER.
